UNITED STATES PATENT OFFICE.

MALCOLM McLENNAN, OF MONROE, WASHINGTON.

BRAKE MECHANISM.

No. 889,953.

Specification of Letters Patent.

Patented June 9, 1908.

Application filed December 9, 1907. Serial No. 405,832.

To all whom it may concern:

Be it known that I, MALCOLM McLENNAN, a citizen of the United States of America, and a resident of the town of Monroe, in the 5 county of Snohomish and State of Washington, have invented certain new and useful Improvements in Brake Mechanism, of which the following is a specification.

My invention relates to improvements in 10 brake mechanism and aims primarily to provide an efficient ratchet operating device, particularly adapted for use on logging trucks, which is comparatively simple in construction, embracing but few parts which are 15 not liable to be readily broken.

A further object resides in the provision of 20 a device of this character which can be readily secured to or removed from the winding shaft of the brake mechanism, as desired.

Other objects will be set forth as the 25 description progresses and those structural features and combinations of parts, in which the invention resides, succinctly defined in the appended claims.

Referring now to the accompanying drawing, in which like numerals of reference indicate like parts throughout the several views: Figure 1 is a view in side elevation of a logging truck with parts broken away, showing 30 my invention applied to the brake mechanism thereof. Fig. 2 is a fragmentary top plan view thereof. Fig. 3 is a view in perspective of the ratchet device removed from the winding shaft, a portion of one section of 35 the housing being broken away, and Fig. 4 is a sectional view of the ratchet device.

In the accompanying drawing I have illustrated my improved ratchet mechanism applied to the winding shaft 1 of the brake 40 mechanism of a logging truck 2, of well known construction. Winding shaft 1 is horizontally disposed and has one end portion projecting outwardly beyond one side of the truck, whereby said shaft can be operated 45 while the truck is in motion by a person standing alongside of the track, as is well understood. This projecting end portion of shaft 1 is reduced in diameter to provide a shoulder 1', and from said shoulder outwardly is formed square in cross section for 50 reception of the ratchet wheel 3 of my improved device. Ratchet wheel 3 is held firmly against shoulder 1' by a nut 4.

Reference numeral 5 indicates a housing in 55 which ratchet wheel 3 is received, said housing being formed of two longitudinal sections

supported for rotation on the unthreaded end portion of said ratchet wheel, as clearly illustrated in Fig. 4. The component sections of housing 5 are provided with extensions 5', formed with recesses which provide a socket 6^a for reception of an operating handle 6.

Reference numeral 7 indicates suitable dogs which are pivotally mounted in recesses 65 provided in the contiguous faces of the respective sections of housings 5 by pins 8. These dogs are yieldingly held in engagement with the teeth of ratchet wheel 3 by springs 9. The outer section of housing 5 is formed 70 with an opening 10 through which nut 4 can be removed when it is desired to remove the entire device from shaft 1. Bolts 11 are employed for securing the sections of housing 5 together.

To inspect the interior of the ratchet device when it is in position of shaft 1, it is merely necessary to remove the outer section of housing 5, this being accomplished by removing the bolts 11 and bolts 11', the latter of 80 which secure handle 6, against accidental displacement.

Reference numeral 12 indicates the ordinary pawl and ratchet mechanism for preventing accidental unwinding of shaft 1.

By my invention the brake mechanism of a logging truck can be set in a more efficient manner than by the means now employed, and further it will be observed that handle 6, when occupying the position illustrated in 90 Fig. 1, as when not in use, will not be injured should it strike an obstruction, as it is free to swing, as will be readily understood. If desired, handle 6 need not be secured in the socket 6^a, being only inserted by the brake-man, when it is desired to apply the brakes.

While I have herein shown and described a preferred embodiment of my invention which will operate in a satisfactory manner, I reserve the right to make changes and alterations in the minor details of construction as defined in the appended claims.

Having thus described my invention, what I claim as new and desire to secure by Letters Patent of the United States of America, is:

1. In combination with the truck and brake mechanism thereof including winding shaft projecting outwardly from the side of said truck, a ratchet mechanism comprising a ratchet wheel fixed to the projecting end 110 portion of said winding shaft and a rotatable carrier in which said ratchet wheel is ex-

ranged, said carrier being provided with dogs engaged with said ratchet wheel and being formed with a socket, and a handle removably arranged in the socket of said carrier.

5 2. In combination with the truck and the brake mechanism thereof including a winding shaft projecting outwardly from one side of said truck, the projecting end portion of said winding shaft being angular in cross section and formed with a shoulder, a ratchet wheel arranged on the projecting end portion of said winding shaft, a nut securing said ratchet wheel against the shoulder of said winding shaft, said ratchet wheel having un-
10 toothed end portions, a housing rotatably supported on the end portion of said ratchet wheel, dogs carried by said housing normally engaging said ratchet wheel, said housing being provided with a socket, and a handle re-
15 movably secured in the socket of said hous-
ing.

3. In combination with the truck and the brake mechanism thereof including a winding shaft projecting outwardly from one side 25 of said truck, the projecting end portion of said winding shaft being angular in cross section and formed with a shoulder, a ratchet wheel arranged on the projecting end portion of said winding shaft, a nut securing said ratchet wheel against the shoulder of said 30 winding shaft said ratchet wheel having un-

toothed end portions, a housing formed in longitudinal sections rotatably supported on the end portions of said ratchet wheel, the said sections of said housing being formed in 3 their contiguous faces with recesses, dogs pivoted in the recesses of the sections of said housing and arranged to engage said ratchet wheel, the outer of the sections of said housing being formed with an opening through 40 which said nut can be removed, means removably securing the sections of said housing together, and a handle secured to said housing.

4. In combination with the winding shaft 45 of a brake mechanism, a ratchet wheel thereon, a housing in which said ratchet wheel is arranged, said housing being formed in longitudinal sections formed with openings through which said shaft projects, a nut on 50 said shaft for preventing displacement of said ratchet wheel, pawls in said housing engaging said ratchet wheel, said housing being formed with a socket, and a handle secured in said socket.

Signed at Monroe, Washington, this 21 day of November 1907.

MALCOLM McLENNAN.
